UNITED STATES PATENT OFFICE

CHARLES L. HUNT AND NETTER J. HILL, OF ST. LOUIS, MISSOURI, ASSIGNORS TO NON-REFILLABLE CONTAINER, INC., OF ST. LOUIS, MO., A CORPORATION OF MISSOURI.

LIQUID CONTAINER

Application filed July 11, 1928. Serial No. 291,718.

This invention relates to liquid containers, and has special reference to a container equipped with a novel form of valve device through which the liquid contents of the container may be withdrawn in the usual manner, and which renders it impossible or extremely difficult to refill the container while the valve is in connection therewith.

An object of the invention is to provide an improved valve device for use in connection with liquid containers comprising a pipe extending through the top of the container toward the bottom and having its lower end open and equipped with means for supporting a valve seat, in combination with a support equipped with a valve seat and a valve and means for removably supporting the support and thereby the valve within said pipe.

Another object of the invention is to provide a device for replacing and removing said support from the pipe.

Other objects will appear from the following description, reference being made to the drawing in which

Fig. 1 is a view showing a container equipped with the present invention.

Fig. 2 is an enlarged vertical sectional view of the invention.

Figs. 3 and 4 are cross sectional views on the lines 3—3 and 4—4, respectively, of Fig. 2.

Fig. 5 is a sectional view showing a device for inserting and removing the valve support from the pipe through which the container is filled and emptied.

The container in which the invention is shown is a barrel of familiar construction comprising a shell 1, a top wall 2 and a bottom wall 3.

A pipe 4 extends through a hole in the top 2 to the bottom 3. An impervious joint between the top wall 2 and the upper end of the pipe 4 may be obtained by a ring of solder 5 applied at the joint. The lower end of the pipe 4 has a number of notches 6 so as to permit the liquid contents of the container to be withdrawn through the pipe 4 or to permit the container to be refilled. The inside of the pipe 4 at its upper end is threaded and is closed by a removable plug 7 during shipment or when the container is in storage.

This plug may be removed and the usual threaded attachment of a pump (not shown) may be screwed in place of the plug to withdraw the liquid contents of the container.

A sleeve 8 is secured within the lower end 55 of the pipe 4 above the notches 6. This sleeve is not rotative within the pipe. A cotter pin 9 extends diametrically through the lower ends of the pipe 4 and the sleeve 8 and, if desired, this cotter pin may function to support 60 and hold the sleeve 8 from rotation in the pipe. Or, the sleeve may be otherwise held from rotation. The sleeve 8 is internally threaded at its upper end.

A tubular valve support 10 is exteriorly 65 threaded at its upper end and is insertable in the sleeve 8 until the threads on the outside of the support 10 engage with the threads on the inside of the sleeve 8. When these threads come in contact with each other the 70 support 10 may be screwed into the sleeve 8 until the lower end of said support abuts against the cotter pin 9 and prevents further rotation of said support 10 in the direction in which it must be rotated when it is being 75 screwed into the sleeve 8.

Some distance below its upper end the support 10 is formed with a valve seat 11 having an opening 12; and below the valve seat 11 the support 10 has a valve stem guide 13. A 80 valve stem 14 extends through the guide 13 and on its upper end is equipped with a valve 15 movable to and from the seat 11 to close and to open the opening 12. The valve stem 14 has a nut 16 screwed on its lower end below the guide 13 and this nut serves to limit movement of the valve 15 toward open position.

The device for inserting and withdrawing the valve device is shown in Fig. 5, the same comprising a rod 17 having a plug 18 attached to one end and designed and adapted to be screwed into engagement with threads 19 on the inside of the upper end of the support 10 above the valve seat 11. These threads 19 are formed oppositely from the 95 threads on the outside of the support 10 so that there will be no difficulty in using the device 17—18 to insert and to remove the support 10. Lugs 20 at the lower end of the threads 19 constitute abutments for the plug 100

18 to prevent the same from being screwed so far into the support 10 as to become rigid. The rod 17 has one or more discs 21 functioning as guides when inserted within the pipe 4 so as to hold the rod 17 axially within the pipe. A handle 22 is in connection with the upper end of the rod 17.

Initially the container 1 is filled with oil or other liquid through the pipe 4 before the valve support 10 is inserted, it being understood that the upper end wall 2 is provided with the usual vent (not shown). After the container 1 is filled the support 10 screwed on the plug 18 is passed downwardly through the pipe 4 until the threads on the outside of the upper end of the support 10 engage the threads on the inside of the upper end of the sleeve 8. When said threads are brought into abutting contact the handle 22 is operated to rotate the rod 17 and thereby the plug 18 and the support 10 which is screwed on said plug. Such rotation is in a direction necessary to screw the support 10 into the sleeve 8 and continues until the lower end of the support 10 abuts against the cotter pin 9. Then continued rotation of the plug 18 in the same direction unscrews the same from the support 10 and the plug, together with the rod 17, is withdrawn from the pipe 4. Then the plug 7 is applied and kept in connection with the device so long as the container is in shipment or in storage.

When it is desired to withdraw the liquid contents of the container the plug 7 is removed and a pump is secured in connection with the upper end of the pipe 4 in the same way that the pump is usually attached to the opening in the top of an oil barrel. When the pump is operated the valve 15 will, of course, be raised, permitting the liquid contents of the container to be pumped out. But, the container cannot be refilled so long as the valve support 10 remains in position in the pipe, for the valve 15 prevents inflow of liquid. When it is desired to refill the container the device 17-18 must be screwed into engagement with the threads 19 and continuously rotated until the support 10 is unscrewed from the sleeve 8. When the support 10 becomes disengaged from the threads on the sleeve 8 the attaching and detaching tool may be withdrawn and with it the support 10 will be withdrawn from the pipe 4. Then, it is apparent that the container may be refilled. The construction, arrangement and relationship of the parts may be varied within equivalent limits without departure from the nature and principle of the invention.

We do not restrict ourselves in unessential respects, but what we claim and desire to secure by Letters Patent is:

1. In a container having upper and lower end walls, a pipe extending through one of said walls toward the other, a valve support, a threaded element for supporting said valve

support within the inner end of said pipe, an abutment for the inner end of said valve support, a valve seat in said valve support, a valve movable to and from said seat, and means for guiding said valve.

2. In a liquid container having upper and lower end walls, a pipe extending from the upper end wall toward the lower end wall, internal screw threads within the lower portion of said pipe, a cylindrical valve support, external screw threads on one end of said valve support screwed into said first-named screw threads, a valve supported within said valve support, and a device for operating said valve support to screw the same in position and to unscrew the same for removal from said pipe.

3. In a container having opposite end walls, a pipe extending through one of said end walls toward the other and having lateral openings at its inner end, a sleeve secured within the inner end of said pipe above said openings, a cylindrical valve support removably supported in said sleeve, an abutment limiting extent of inward movement of said valve support in said sleeve, and a valve supported in said valve support.

4. In a container having opposite end walls, a pipe extending through one of said end walls toward the other and having lateral openings at its inner end, a sleeve secured within the inner end of said pipe above said openings, a cylindrical valve support removably supported in said sleeve, an abutment limiting extent of inward movement of said valve support in said sleeve, a valve supported in said valve support, and means in the outer end of said valve support outwardly beyond said valve for engaging with a positioning and removing tool.

5. In a container having upper and lower end walls, a pipe having its upper end opening through one of said end walls and extending downwardly toward the other and opening laterally into said container near said other end of said container, a cylindrical valve support of less diameter than the inside of said pipe between said support and the upper end of said pipe screwed into said pipe near the end of said pipe which opens laterally into said container as aforesaid, means limiting extent of movement of said valve support toward said other end of said container and preventing said valve support from closing communication from said pipe to said container, and a valve supported within said valve support.
